GOVERNOR VALVE FOR VARIABLE PITCH PROPELLERS

Chester M. Jedrziewski, Manchester, Conn., assignor to United Aircraft Corporation, East Hartford, Conn., a corporation of Delaware

Application January 23, 1948, Serial No. 3,955

4 Claims. (Cl. 170—160.2)

1

This invention relates to an improved control valve and finds particular utility when used in a governor controlling the pitch of a hydraulically controlled pitch propeller.

An object of this invention is an improved control valve.

Another object of this invention is to increase the sensitivity of a speed governor controlled valve.

A further object of this invention is a speed control system whose normal automatically controlled range is controlled by a governor containing a valve that directs hydraulic fluid to a speed changing mechanism and in which the governor acts as a single acting governor except for large speed changes when it is double acting.

A still further object resides in the provision in a speed-governor, controllable-pitch-propeller system of the character described of controllable resilient means for opposing centrifugal twisting moments acting on the propeller blades to prevent them from turning or allowing them to turn toward low pitch for small speed changes in combination with other controllable resilient means for assisting the centrifugal twisting moments acting on the propeller blades to turn the blades toward their low pitch for large speed changes.

Other objects and advantages will be more particularly pointed out hereinafter or will become apparent as the description proceeds.

In the accompanying drawings in which like reference numerals are used to designate similar parts throughout, there is illustrated a suitable mechanical embodiment of what is now considered to be the preferred form of the invention. The drawings, however, are for the purpose of illustration only and are not to be taken as limiting the scope of the invention as set forth in the appended claims.

In the drawings,

Fig. 1 is a diagrammatic illustration of the principal elements of a controllable pitch propeller system including a constant speed governor embodying the invention.

Fig. 2 is a sectional view on a somewhat enlarged scale of a valve and valve housing in a governor illustrating the "on speed condition."

Fig. 3 is a view of the valve and valve housing illustrated in Fig. 2 showing the "over-speed condition" or "on-speed condition" if leakage is present.

Fig. 4 is a view of the valve and valve housing illustrated in Fig. 2 showing the "under-speed condition."

Fig. 5 is a view of the valve and valve housing

illustrated in Fig. 2 showing the "major under-speed condition."

The invention forming the subject matter of the application has been shown in connection with a propeller of the type shown in U. S. Patent No. 2,402,065, Propeller Control, issued to Erie Martin June 11, 1946, and 2,280,714, Feathering Propeller Control issued to Erie Martin April 21, 1942, which references may be taken for a more complete disclosure. This propeller has been only diagrammatically illustrated in Fig. 1 in which a propeller generally indicated by numeral '10, includes a hub '12, splined to the propeller drive shaft '14 and provided with a plurality of radially disposed blade receiving sockets '16, only one of which is indicated. The usual propeller hub spider connecting the propeller blades and the propeller drive shaft, has been omitted for simplicity. A propeller blade '18 is mounted in each socket in the usual manner with suitable anti-friction bearings '20 interposed between a socket abutment '22 and flange '24 on the inner end of the blade so that the blades are freely rotatable about their axes in pitch changing directions. Each blade '18 is provided on its inner end within the hub member '12 with a gear sector '26 all of which gear sectors mesh with a master gear '28 journalled in the hub member '12 and rotatable about the axis of shaft '14. Master gear '28 is integral with a rotatable cam '30 rotated through a cam and follower mechanism including piston carried cam followers, the shaft of one of which is shown at '32, and cooperating oppositely directed stationary and movable cam slots, one of which is indicated at '34. The cam followers '32 are carried by an annular piston '36, reciprocable in a cylinder '38 having a dome-shaped outboard end, the piston having a tubular hub provided with a sleeve mounted for reciprocation on a tubular shaft extension formed by a threaded tube carried by shaft '14. From the above description and reference, it will be evident that a preponderance of oil pressure upon either side of piston '36 will cause the piston to move and change the pitch of all of the propeller blades '18 in unison.

Oil is conducted from a governor, generally indicated at '40, to cylinder '38 through two fluid conduits '44 and '46 and communicating channels '48 and '50 leading into propeller hub. The governor '40 acts to selectively connect one of the lines '44, '46 to governor pressure and to connect the other line with drain in order to move piston '36 and change the pitch of the propeller blades the required amount to maintain constant speed

of the engine and propeller. Fluid is distributed to either side of the piston 36 by means well known to the art and particularly illustrated in Patents 2,402,065 and 2,280,714, referred to above. It will be understood that when one side of the piston is connected to pressure fluid through one of the above fluid lines, the fluid on the other side of the piston is connected to drain through the other line in the usual manner.

The governor is shown diagrammatically in Fig. 1 to which reference is now made. The governor comprises a rotatable shaft 52 driven by gear 42 which engages a gear (not shown) carried by the propeller drive shaft 14 in timed relation with the engine. A flange 54 which is fixed to the upper end of shaft 52 pivotally supports a pair of fly weights 56. The shaft 52 may be made in a single piece, as shown, or if desired may comprise several sections connected together, as by splined joints.

Intermediate its ends the shaft 52 carries a gear 58 meshing with a gear 60 supported on a hollow axle journaled in a governor body 62 to form a booster pump. Hydraulic fluid is supplied to this pump from any convenient source, the source herein being the engine lubricating pump 64 which is supplied through a conduit 66 from the engine oil tank, or reservoir 67 and discharges through conduit 68, duct 70 and branch passage 72 to the intake of the booster pump. A relief valve 71 limits the pressure in conduit 68 and in conduit 69 leading to the engine lubricating system. Oil from the booster pump flows through channel 74, through ports in hollow shaft 52 into annular pressure chamber 76 between lands 78 and 80 of a hollow piston rod of a governor pilot valve 82 which is vertically reciprocable in the hollow shaft 52 by the fly weights 56 and speeder spring 84 which act oppositely on an anti-friction bearing flange 86 on piston rod 82.

When the pilot valve 82 is forced upwardly by an increase in governor revolutions per minute reacting upon the fly weights 56 to overcome the balance between said fly weights and speeder spring 84, hereinafter called "overspeed condition," pressure oil supplied by the booster pump 58, 60 flows from chamber 76 through ports in shaft 52 to channel 88 which communicates to conduit 46. When the pressure oil is connected to conduit 46, the conduit 44 is connected to drain through channel 90 suitable ports in shaft 52 and chamber 91 in piston rod 82 beneath the land 80 to the booster pump inlet channel 70 thus establishing a drain through relief valve 71 of conduit 69 for oil on the inboard low pitch side of the pitch changing piston 36. The result of admitting governor pressure fluid through conduit 46, is, as previously described, to move the piston 36 inboard, i. e., to increase the pitch of the blades 18, with a resultant decrease in revolutions per minute.

As the governor fly weights 56 slow down they permit the speeder spring 84 to depress the piston rod of valve 82 so that the land 78 closes off the pressure governor fluid passing from chamber 76 to channel 88 when the selected speed setting of the governor has been reached, hereinafter called "on speed condition."

If the governor speed is substantially reduced below the selected speed setting, pressure fluid in chamber 76 will be admitted past the land 80 to channel 90 and conduit 44 to the inboard low pitch side of piston 36 to move piston 36 toward the low pitch position, while the fluid

on the outboard side of piston 36 will be drained through conduit 46, channel 88, past land 78 into chamber 102 to the hollow stem of pilot valve 82 into the intake channel 70 of the governor booster pump hereinafter called "underspeed condition."

A pressure relief valve 92 is provided in the governor booster pump discharge passage as is usual in this type of governor. Pressure fluid that enters fly weight housing 96 or chamber 98 that would tend to force piston rod 82 down is vented through channels 100 and 94 into hollow drive shaft 52, thence into a suitable reservoir such as the engine crankcase.

The constant speed, double-acting governor as previously described in general, will now be treated in more detail to demonstrate the novel features and advantages of this invention.

The lands 78 and 80 on pilot valve 82 are substantially the same width axially as the width axially of their adjacent ports in shaft 52. The axial spacing between lands 78 and 80 is less than the axial spacing between their respective adjacent port spacing. Consequently lands 78 and 80 cannot completely cover their respective ports simultaneously. As this invention is embodied in an actual operating governor and propeller, a differential spacing of .012 inch between lands 78 and 80 and their adjacent ports has proven successful and satisfactory.

Each of the lands 78 and 80 have two major sides which terminate in edges which cooperate with respective edge portions of their adjacent ports. In other words, the edge of one major side of each land will control pressure flow while the edge of the other side will control drain flow in cooperation with the cooperating edge portions of the respective adjacent port. The foregoing then applies to the terms "drain and pressure controlling edges" as used herein.

When the propeller and governor are in the "onspeed condition" (Fig. 2) land 78 will cover its adjacent port closing off channel 88 from chamber 76, maintaining pressure against the high pitch side of the pitch changing piston 36 balancing the forces in the blades 18 tending to force them to low pitch. Land 80 does not completely cover its adjacent port thus permitting fluid on the low pitch side of the pitch changing piston 36 to drain through channel 90 into chamber 91 thence to duct 70. The forces holding the propeller at the blade pitch necessary to maintain the predetermined speed are the forces in the blade, such as aerodynamic forces which may tend to turn the blades in either direction and centrifugal twisting moments which tend to force the blades 18 toward low pitch and fluid pressure on the high pitch side of the pitch changing piston 36 tending to force the blade toward high pitch and drain pressure on the low pitch side of piston 36 tending to force the blade toward low pitch. In this condition, the governor is performing as a single-acting governor.

Referring to Fig. 3, if there is any leakage of the pressure fluid from the high pitch side of the pitch changing piston or its connecting channels, passages or ports, the forces in the blades 18 tending to reduce the propeller pitch will become greater than the fluid pressure acting on piston 36 tending to increase the propeller pitch causing the blades 18 to move to a lower pitch resulting in a slight increase in revolutions per minute of the propeller and governor. The increased revolutions per minute will cause fly

weight 56 to raise piston rod and pilot valve 82 a small amount resulting in land 78 uncovering its adjacent port permitting pressure fluid to flow from chamber 76 to flow into channel 88, 46, 48 to the high pitch side of the pitch changing piston 36 causing it to increase the pitch of blades 18, resulting in a restoration of the propeller and governor to the selected speed setting. After reaching this onspeed condition sufficient fluid will continue to flow past land 78 into the channel 88 to just make up for the leakage. The raising of piston rod and pilot valve 82 causes the land 80 to further uncover its adjacent port permitting fluid to continue to drain from the low pitch side of the pitch changing piston 36. The position of the pilot valve 82 and its lands 78 and 80 with respect to their adjacent ports under this "onspeed condition" when there is slight leakage is substantially the same as an "overspeed condition" with no leakage. The governor is still performing as a single acting governor. The forces acting upon the pitch changing pistons 36 are the forces in the blades 18 tending to turn said blades 18 toward low pitch and the opposing fluid pressure acting upon the high pitch side of the pitch changing piston 36, the low pitch side of the pitch changing piston 36 is open to drain.

If the power of the engine to which the propeller is attached is decreased or flight conditions of the airplane to which the engine and propeller are attached should alter causing the propeller revolutions per minute to increase, an "overspeed condition" will result and a cycle of governor and propeller operation similar to that described above for slight leakage will take place so that the selected speed setting of the propeller and governor will be restored.

Referring to Fig. 4, the "underspeed condition," small decreases of propeller and governor speed over the selected speed setting caused by small power decreases of the engine to which the propeller and governor are attached or variations of flight conditions of the airplane to which the engine, propeller and governor are attached, will cause the speeder spring 84 to force the piston rod and pilot valve down, land 78 to uncover its adjacent port permitting fluid to drain from the high pitch side of the pitch changing piston 36 into chamber 102. Land 80 will not have moved sufficiently downward to cover its adjacent port, permitting fluid to drain from the low pitch side of the pitch changing piston 36. Both sides of piston 36 are now connected with drain. The only unbalanced forces acting upon the pitch changing piston 36 are those in the blades 18 tending to turn said blades 18 to low pitch. The rate of change of pitch to low pitch is determined by the rate of fluid flow past land 78 to drain. This condition will prevail until the propeller and governor have been returned to the selected speed setting when the fly weights 56 will balance the force of the speeder spring 84 and return the piston rod and pilot valve 82 to the "onspeed condition," as in Fig. 2. The governor is acting as a single-acting governor in this condition.

It has been found in practice that the speed of a propeller and governor containing this invention while operating at a constant speed setting and attached to an airplane operating under normal conditions of level flight generally will vary not more than 0.2 of 1% of the selected speed setting. During most conditions of turbulent weather, the variation generally will not exceed

0.4 of 1% of the selected speed setting. Speed changes of the above magnitude, i. e. .2 of 1% and .4 of 1%, are small speed changes and insufficient to move valve 82 so that land 80 covers its adjacent port opening into channel 90. The governor containing this invention while operating in the conditions stated above is functioning as a single-acting governor.

If the power of the engine to which the propeller and governor are attached is substantially decreased or the airplane to which the engine, propeller and governor are attached is caused to enter a climb attitude, the propeller and governor speed will be reduced considerably below the selected speed setting. Referring to Figs. 1 and 5, this considerable reduction-major underspeed-will cause the speeder spring 84 to move the piston rod and pilot valve 82 down to a position where land 80 uncovers its adjacent port permitting pressure fluid to flow from chamber 76 to channel 90, 44, chamber 43 to the low pitch side of the pitch control piston 36, causing the pitch of blades to be reduced. Land 78 has uncovered its adjacent port permitting fluid to drain from the high pitch side of the pitch changing piston 36 through channel 88 into chamber 102. The governor pressure fluid exerting force on the low pitch side of the pitch changing piston 36 assists the centrifugal twisting moment in reducing the pitch of blades 18, restoring the propeller and governor speed to the selected speed setting more rapidly. The governor is acting as a double-acting governor in the condition described immediately above.

35 The improved governor pilot valve which is the subject of this invention embodying lands axially spaced differentially from the axial spacing of the ports adjacent said lands gives a greater sensitivity to speed changes imposed upon the 40 governor than a governor pilot valve in which the axial spacing of the lands is identical with the axial spacing of ports adjacent said lands as formerly incorporated in double-acting governors as applied to aeronautical propellers of the type previously described.

45 In a governor pilot valve having lands and adjacent ports axially identically spaced, two different hydraulic centering forces act upon the valve tending to cause it to move to a position of closing off both ports before the governor has 50 reached the selected speed setting and balance between the fly weights and opposing spring forces. The action of the hydraulic centering forces that tends to close the ports at small openings reduces the sensitivity of the governor to 55 small changes of speed. Test results of a propeller-governor combination show the non-effective range generally to be plus or minus 10 R. P. M.

60 Referring to Fig. 3, pressure fluid in chamber 76 will flow past land 78 into channel 88 with a velocity causing a reduced pressure immediately below the under face of land 78 according to Bernoulli's theorem. The fluid pressure acting upon the upper face of land 80 being static will be greater than that acting upon the under face of land 78 thus tending to force the pilot valve 82 downward closing off the port prematurely.

65 A similar hydraulic centering force will occur in cavity 91 with a greater fluid pressure acting upon the upper face of land 106 than on the under face of land 80 because of the velocity past land 80.

70 With lands and adjacent ports identically axi-

ally spaced, the aforementioned hydraulic centering forces will cooperate to give a combined force that is approximately twice the intensity of the individual force. With lands and adjacent ports differentially axially spaced, one hydraulic centering force is eliminated by virtue of one port opening being sufficiently large to reduce the orifice effect to a negligible quantity. Test results of the previously mentioned propeller-governor combination indicate that the elimination of one hydraulic centering force reduces the non-effective range of the governor by half, i. e., to plus or minus 5 R. P. M.

It is to be understood that the invention is not limited to the specific embodiment herein illustrated and described, but may be used in other ways without departure from its spirit as defined by the following claims.

I claim:

1. In combination with a controllable-pitch propeller having a double-acting hydraulically-actuated pitch changing device and having blades continuously urged in one pitch changing direction, a governor comprising speed responsive means and a control valve having a spool-type element movable thereby, said valve having two permanently spaced ports connected with opposite sides of said propeller actuating means and two permanently spaced lands carried by said element and controlling said ports, each of said lands being of substantially the same width as the port with which it cooperates, said ports and lands being relatively movable, a pressure connection and a drain connection, one of said connections permanently opening between said lands and the other of said connections permanently opening on the other sides of said lands, said ports being spaced differently than said lands, the difference in said spacing being less than the width of said ports and lands whereby both of said ports are simultaneously opened to said drain by said lands when both said ports are blocked by said lands from the pressure connection.

2. In combination with a controllable-pitch propeller having a double-acting hydraulically-actuated pitch changing motor, and having blades continuously resiliently urged in one pitch changing direction, a governor comprising a control valve and speed responsive means for operating said valve, said valve comprising cooperating relatively movable ports and lands of substantially the same width, each land having two major sides terminating in edges which respectively control pressure and drain fluid in cooperation with the adjacent edge portion of its respective port, said lands being permanently spaced from each other a predetermined distance differing from the port spacing by an amount less than the width of each of said ports, said valve having a pressure connection and a drain connection, one of said ports being connected with one side of said double-acting pitch changing motor and selectively connectable by said valve with either said pressure or said drain connection, the other of said ports being connected with the other side of said motor and selectively connectable by said valve with either said drain or said pressure connection, one of said pressure and drain connections permanently opening between said lands and the other of said connections permanently opening on the other sides of said lands, the drain controlling edges of said lands being closer to said pressure connection

for the respective land than the corresponding drain controlling edges of said ports, and the pressure controlling edges of said ports being spaced at least as far from the pressure connection for the respective port as the corresponding pressure edges of said lands.

5 3. In combination with a controllable-pitch propeller having a double-acting hydraulically-actuated pitch changing motor, and having blades continuously resiliently urged in one pitch changing direction, a governor comprising a control valve and speed responsive means for operating said valve, said valve comprising cooperating relatively movable ports and lands of substantially the same width, each land and its cooperating port having cooperating drain controlling edges, said ports being permanently spaced from each other a predetermined distance, said lands being permanently spaced from each other a predetermined distance differing from the port spacing by an amount less than the width of each of said ports, said valve having a pressure connection and a drain connection, one of said ports being connected with one side of said double-acting pitch changing motor and selectively connectable by said valve with either said pressure or said drain connection, the other of said ports being connected with the other side of said motor and selectively connectable by said valve with either said drain or said pressure connection, one of said pressure and drain connections permanently opening between said lands and the other of said connections permanently opening on the other sides of said lands, the drain controlling edges of said lands being closer to said pressure connection for the respective land than the corresponding drain controlling edges of said ports so that the port connected with the side of the pitch changing motor opposing movement of the propeller blades in said one direction may be connected with either pressure or drain while the other side remains connected with drain.

40 4. In combination with a controllable pitch propeller having a double-acting hydraulically-actuated pitch changing motor, and having blades continuously resiliently urged in a pitch reducing direction, a governor comprising a control valve and speed-responsive means for operating said valve and controlling said propeller, said valve comprising relatively movable cooperating ports and lands, said ports being spaced from each other at predetermined distance and said lands being spaced from each other a predetermined distance differing from said port spacing by an amount less than the width of each of said ports, said valve having a pressure connection and a drain connection, one of said ports being connected with one side of said double-acting pitch changing motor and selectively connectable by said valve with either said pressure or said drain connection, the other of said ports being connected to the other side of said double-acting pitch changing motor and selectively connectable by said valve with either said drain or said pressure connection, one of said connections permanently opening between said lands and the other of said connections permanently opening on the other sides of said lands, said lands being closer to said pressure connection for the respective land than said ports so that the pitch increasing side of said motor may be selectively connected with pressure or drain while the pitch reducing side of said motor is connected with drain whereby the governor and propeller may

act as single acting devices for small speed variations but may act as double acting devices for greater speed variations.
